UNITED STATES PATENT OFFICE.

JULIUS H. GUGLER AND GEORGE W. COLLES, OF MILWAUKEE, WISCONSIN; SAID COLLES ASSIGNOR TO SAID GUGLER.

PRIMARY-BATTERY CELL.

1,073,677.

Specification of Letters Patent. Patented Sept. 23, 1913.

Application filed July 22, 1910. Serial No. 573,184.

To all whom it may concern:

Be it known that we, JULIUS H. GUGLER and GEORGE W. COLLES, of Milwaukee, Wisconsin, have invented a Primary-Battery Cell, of which the following is a specification.

This invention relates to primary electric batteries and our object is to produce an improved form of cell for commercial use which will give a very high electromotive force, a low internal resistance, extreme constancy of action, and low cost of maintenance; and further which shall not have serious objections such as giving off of noxious or corrosive gases or the continued corrosion of the anode on open circuit.

Chlorate of potash has been heretofore used or tried as a depolarizer for battery cells; but as heretofore used it has been practically a total failure. We have found that the reason for this lies in its very low solubility and in the density of its solution. Unlike other depolarizers, it does not uniformly diffuse itself and come into action when placed all in one spot or upon the bottom of the cell, but, as its aqueous solution contains but a small portion of the chlorate, that quantity is soon used up and depolarization promptly ceases. An extra supply, if merely placed upon the bottom of the cell and left to take care of itself, will saturate the liquid with such extreme slowness that it is of no practical benefit. Unless therefore, some mechanical means for keeping the solution constantly saturated be devised, potassium chlorate cannot be used commercially. We have found that this may be accomplished by taking advantage of the density of the solution so as to produce an automatic circulation, provided the potassium chlorate is properly disposed in the cell. To this end according to our invention the undissolved potassium chlorate supply is supported at some point above the bottom of the cell, and preferably toward the top where the greatest effect is to be obtained, whereby as it slowly dissolves the solution sinks downwardly, and the lighter unsaturated portion of the liquid takes its place, the solution being thus kept saturated by convection. There is, however, another danger to be avoided. While it is necessary for successful operation that the solution shall be quite thoroughly saturated with

chlorate, on the other hand any excess or 55 tendency to excess in that portion of the electrolyte through which the current is passing results in a deposit of chlorate upon the surface of the cathode, and consequent gradual polarization. If this action is continued for a sufficient length of time the negative element becomes insulated through a coating of potassium chlorate, and this result also we are enabled to avoid by our construction. 60

The nature of our invention is more exactly specified in the following detailed description and specifically set forth in our claims.

In the accompanying drawings, we have 70 illustrated by way of example three embodiments of our invention, and herein—

Figure 1 is a longitudinal section through one form of cell, this being a two-liquid form, constructed according to our invention; Fig. 2 is a longitudinal section through a second form, this being a one-fluid form; and Fig. 3 shows in longitudinal section a third form of cell, also a one-liquid cell. 75

The reference letters refer each to the 80 same part in each figure of the drawings.

In Fig. 1 is shown a battery-jar or container *a*, a cylindrical zinc anode *b* immersed in an acid electrolyte *e*, a porous cup *d* containing the depolarizing liquid *c*, and a cylindrical carbon negative element *f* having a suitable circuit-connector *g*. The top of the cylinder *f* is considerably below the level of the liquid *e*, and a quantity of fragmental material *h*, such for example as sand, gravel, glass or brick-fragments, coke-breeze or granulated carbon, fills the bore of the carbon element *f* and extends some distance above the top thereof, being preferably of gradually increasing fineness from the bottom upward as shown. We have used granulated carbon to good advantage for this purpose, as it forms an increased surface for the action of the depolarizer. On the top of this bed of fragmental material is placed the extra supply of potassium chlorate *i* immersed in the liquid *e*, or at least soaked thereby. It is important that the bed of fragmental material be of sufficient thickness above the carbon to prevent any 95 undissolved chlorate from getting between the carbon and porous cup *d*, for this would 100 immediately result in a notable increase in

the internal resistance of the cell, the chlorate being in its solid form a good insulator. As so disposed, the chlorate gradually dissolves in the liquid, and the saturated liquid 5 around the undissolved chlorate gradually sinks to the bottom, filtering through the bed of fragmental material, while the unsaturated portion at the bottom rises and takes its place; in this manner keeping the liquid 10 in a constant state of saturation.

10 We found that, while the chlorate when placed at the bottom of the cell, has after a few minutes almost no effect and the internal resistance to depolarization rapidly 15 rises, as soon as the chlorate is raised and supported at the top in the manner designated, the electromotive force rises to over two volts and remains constant at that pressure.

20 In Fig. 2 we have shown another means of support for the chlorate, such means being adapted to support it at varying heights and thus compensate for varying temperatures or output. The elements *a*, *b* and *c* 25 are the same as in Fig. 1, while to illustrate the application of the invention to a one-fluid-cell, the porous-cup *d* is here replaced by a perforated separator *j*, and the carbon *f'* is made in the form of a cup or tube 30 closed at the lower end. In the bore of the carbon *f'* is placed a tray or carrier *k*, which may be made of hard rubber or other material that is not acted on by the chemicals, 35 having a perforated bottom *m*, and supported by a vertical rod *n*, also of hard rubber or other non-corrodible material, which passes upward through a hole in the cross-bar *o* and has a shiftable screw-collar *p* provided with a set-screw *q* thereon whereby the 40 rod *n* may be raised and lowered and the tray *k* correspondingly. On the bottom of the tray is placed preferably granulated carbon *r* and on the bed of granulated carbon is disposed the extra supply of potassium 45 chlorate *s*.

As the electromotive force of the cell varies somewhat according to the temperature of the atmosphere, this can be compensated by varying the height of the tray *k*, 50 and it can be correspondingly varied to compensate the varying out-put of the cell so as to give a constant external voltage. For example, when the cell is being worked on a high current-output, the tray *k* will be 55 raised to the top of the solution, and when it is working at a low output or at infrequent intervals, the tray may be depressed to near the bottom. This avoids unnecessary waste of chlorate and the evolution of 60 chlorin which is not only unused but dissipates the energy of the depolarizer and produces disagreeable odors and corrosion in the apartment where the cell is located.

In the third form of our invention, we 65 have shown in conjunction with the con-

tainer *a* and separator-plate *j* an internal anode *b'* and an external cylindrical cathode *f''*. Around the external periphery of the cathode and near the top of the electrolyte *c* is disposed a perforated annular shelf *t*, 70 which may be supported there upon a shoulder *u* formed on the carbon or upon lugs *v* formed around the inside surface of the container *a*, or both as may be desired, and where both are used, the shelf may be made 75 in several sections. On this shelf is disposed a quantity of fragmental material *w* on top of which is placed the undissolved supply of potassium chlorate *x*, and as before, said supply will gradually pass into 80 solution and the solution will be diffused by downward convection throughout the electrolyte.

It will be seen that in each of our arrangements, but more especially in Figs. 2 and 3, 85 the construction is such as to confine the saturated solution of chlorate principally or wholly to that portion of the electrolyte which is on the side opposite from the anode. The effect of this is during operation to prevent the chlorate from dissolving too rapidly and thus causing it to be precipitated through electrolytic action upon the surface of the cathode in the manner hereinabove alluded to. As long as the cell is out of 90 action, a saturated solution of chlorate will, of course, exist in the space opposite the anode chamber, and by percolation through the porous cathode or cup this solution will reach the anode chamber; but as long as no 95 current is running, there is no danger of a deposit on the cathode. As soon as the cell is in action, the current may at first cause a slight deposit upon the cathode, but the state of saturation is reduced immediately to the 100 condition where this depositing action ceases, as new chlorate cannot reach the anode space rapidly enough to permit the deposit to continue. Perhaps it is more theoretically 105 correct to state that the requisite condition 110 for proper action is that of sub-saturation, that is to say, where the active electrolyte is just short of complete saturation by the chlorate. As the current continues polarization will, of course, be prevented by the 115 accession of additional chlorate solution by osmotic diffusion through the walls of the cathode. This is practically true of Fig. 1 as well as of the other figures, because the narrowness of the space between the 120 cathode *f* and porous cup *e* is such as to permit little or no appreciable quantity of saturated solution to reach the active portion of the electrolyte through this space.

We wish it understood that our invention 125 is not limited to the use of all the above described features and constructions, for some may be omitted and others may be varied or modified in various ways, as will readily occur to those skilled in the art. For 130

example, sodium chlorate and possibly other chlorates may be substituted for potassium chlorate.

Having thus described our invention, 5 what we claim as new and desire to secure by Letters Patent is:

1. In combination with an electric battery cell having a depolarizer consisting of a solution of a chlorate, an extra supply of 10 undissolved chlorate supported at a variable elevation in the solution.

2. In combination with an electric battery cell having a depolarizer consisting of a solution of a chlorate, a support above the 15 bottom of said solution, a quantity of fragmental material resting on said support, and a quantity of undissolved chlorate resting on said fragmental material.

3. In combination with an electric battery 20 cell having a depolarizing liquid containing a chlorate in solution, a carrier of sheet-material having a perforated bottom supported in said solution above the bottom thereof, a quantity of fragmental material 25 resting on said carrier, and a quantity of undissolved chlorate resting on said fragmental material.

4. In combination with an electric battery 30 cell having a depolarizing liquid containing a chlorate in solution, a carrier of sheet-material having a perforated bottom supported in said solution at or near the top thereof, a quantity of fragmental material 35 resting on said carrier, and a quantity of undissolved chlorate resting on said fragmental material.

5. In combination with an electric battery 40 cell having a depolarizing solution containing a chlorate in solution, a support in said solution, means for raising and lowering said support, and a quantity of undissolved chlorate resting on said support.

6. In combination with an electric battery 45 cell having a depolarizing solution containing a chlorate in solution, a support in said solution, means for raising and lowering said support, a quantity of fragmental material on said support and a quantity of undissolved chlorate on said fragmental material.

7. An electric battery cell comprising, in 50 combination, a container, an anode, a tubular cathode, an electrolyte, and a depolarizing solution containing a chlorate within said tubular cathode; a carrier disposed in the tubular bore of said cathode, means for supporting said carrier at various elevations

in the liquid, and an extra supply of undissolved chlorate supported on said carrier.

8. A two-compartment electric battery 60 cell comprising an anode, a cathode, a liquid electrolyte in the compartment containing the anode, a liquid depolarizing solution in the other compartment, a quantity of solid chlorate loosely supported in a position 65 over a portion of the liquid depolarizing solution, said solution having free access to the lower surface thereof and there being a sufficient distance between the solid chlorate and the active surface of the cathode to prevent the formation of a non-conducting deposit on the cathode.

9. An electric battery cell comprising in combination a container, a substantially imperforate porous cathode substantially dividing the space in said container into two chambers, an anode and an electrolyte in one of said chambers, a liquid chlorate solution in the other chamber, and an extra supply of undissolved chlorate in said last 80 named chamber supported above the bottom of said chlorate solution whereby the solid chlorate as it dissolves diffuses downwardly by gravity so as to replenish the supply of chlorate in said solution, said 85 chlorate reaching the active surface of the cathode by a slow diffusion action therethrough.

10. An electric battery cell comprising in combination a container, a substantially imperforate porous cathode substantially dividing the space in said container into two chambers, an anode and an electrolyte in one of said chambers, a liquid chlorate solution in the other chamber, and an extra supply of undissolved chlorate in said last 90 named chamber supported above the bottom of said chlorate solution whereby the solid chlorate as it dissolves diffuses downwardly 95 by gravity so as to replenish the supply of chlorate in said solution, said chlorate reaching the active surface of the cathode by a slow diffusion action therethrough, and there being a sufficient distance between the solid chlorate and the active surface of the 100 cathode to prevent the formation of a non-conducting deposit on the cathode.

In witness whereof we have hereunto set our hands in the presence of two witnesses.
